(57) **CLAIM**

The ornamental design for a display for device cases, as shown and described.

DESCRIPTION

FIG. 1 is a front elevation view of a display for device cases, showing my new design;

FIG. 2 is a left side elevation view thereof, the right side being a mirror image;

FIG. 3 is a top plan view thereof;

FIG. 4 is a bottom plan view thereof;

FIG. 5 is a top perspective view thereof; and,

FIG. 6 is a front elevation view thereof with environmental structures shown in broken lines.

The rear of the display for device cases is flat and unornamented.

The broken line portion of the figures is included to show unclaimed subject matter only and forms no part of the claimed design.
